(57) CLAIM

The ornamental design for a novelty lighting arrangement, as shown and described.

DESCRIPTION

FIG. 1 is a front elevational view of a novelty lighting arrangement showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof, and showing an environmental structure in broken lines for illustrative purposes only.

The broken lines shown on FIG. 7 are for illustrative purposes only and are hereby disclaimed as forming no part of applicant's claimed invention.

1 Claim, 4 Drawing Sheets

FIG. 1

FIG. 2

FIG. 7
